UNITED STATES PATENT OFFICE.

WILLIAM I. F. HARDEN, OF HARTFORD, KANSAS.

RAILWAY-TIE.

No. 807,377.

Specification of Letters Patent.

Patented Dec. 12, 1905.

Application filed March 23, 1905. Serial No. 251,681.

To all whom it may concern:

Be it known that I, WILLIAM I. F. HARDEN, a citizen of the United States, residing at Hartford, in the county of Lyon and State of Kansas, have invented certain new and useful Improvements in Railway-Ties; and I do hereby declare the following to be a full, clear, and exact description of the invention, such as will enable others skilled in the art to which it applies to make and use the same.

My invention relates to improvements in railway-ties and means of securing rails thereto.

It has for its object to provide a tie which is simple of construction, durable, and yet very cheap of manufacture and in the construction of which a much smaller amount of wood is consumed than is now used for the ordinary wooden tie, the wood to a great extent being replaced by some durable material. The importance of cutting down the vast amount of wood now used for ties, as has been pointed out in my former application, filed October 4, 1904, Serial No. 227,171, (something like eight hundred million ties being now in use in this country,) is generally understood as making it necessary to protect the forests.

The invention consists in the details of construction and combinations of parts herein-after described, and more particularly pointed out in the claims concluding this specification.

In the accompanying drawings, illustrating the preferred embodiment of my invention, which is intended as an improvement on that forming the subject of my previous application hereinbefore mentioned, Figure 1 is a plan view of a sheet of metal marked out for the casing of a tie, showing the position of the rivet and bolt holes therein. Fig. 2 is a perspective view of said casing when bent into shape with the end flaps partly turned in. Fig. 3 is a plan view of a section of track, showing two complete ties and sections of rails in place thereon, each tie having the wood sections arranged differently therein and each having a different style of rail-holding top plate. Fig. 4 is an end view of one of said ties. Figs. 5, 6, and 7 are plan views, respectively, of different arrangements of wood and wood-and-concrete fillings for the upper part of the ties. Fig. 8 is a vertical cross-sectional view taken through the wood filling on the line $\alpha\alpha$ on either of the Figs. 5, 6 or 7. Fig. 9 is a similar view taken through the concrete filling of the upper portion of the tie on the line $\gamma\gamma$ of either Figs. 6 or 7. Fig.

10 is a broken sectional view on the line $\varepsilon\varepsilon$ of Fig. 7, taken through the drain-passage running from the recess holding the wood to the end of the tie. Fig. 11 is a similar view of a different form of wood recess and block therefor, and Fig. 12 is a broken sectional view showing the form of screw-spike which I prefer to use on the inner side of the rails.

While the preferred embodiment of my invention is fully illustrated in the accompanying drawings and its construction and operation is described in the following specification, the right is reserved to make such changes from the constructions shown and described herein as the scope of the claims hereto appended will permit.

In carrying out my invention I cut the casing for the tie from a single sheet of metal, as shown in Fig. 1. The sheet is then bent into the form shown in Fig. 2 with a broad base and a narrower upper portion. Said casing has end flaps which are folded in to close the ends thereof. The broad base of the casing is filled with concrete or similar substance, and strips or blocks of wood of much smaller size than the ordinary wooden tie are placed either together with concrete or alone in the upper part of the casing and bolted in place between the upstanding flanges. Said casing is provided with a series of holes preferably drilled before the sheet is bent in said upstanding flanges and in the upper horizontal portions of the casing. By means of the latter holes angular brace-bars are riveted permanently to the casing with their other flanges provided with perforations registering with the holes in the upstanding flanges of the casing, and bolts are passed therethrough for holding the wooden block in place. Rail-holding plates having their ends turned over to engage the outer flanges of the rails are placed on the top of the tie over the wood blocks and are secured thereto by spikes having their heads engaging the inner flanges of the rails. Said rail-holding plates may be made in various length, as shown in Fig. 3. Where the wooden blocks are arranged inward from the ends of tie drain-passages are formed in the concrete from the wood sockets to the ends of the tie. These sockets may be understepped at one end and the block provided with an extension adapted to project into said stepped portion, whereby it is secured against upward movement at that end and can only be removed from the other end.

Referring more particularly to the draw-

ings, 1 is the bottom of the casing, 2 indicates the sides or vertical portions of the broad base, 3 the upper horizontal portions or steps of said base, and 4 are the upstanding flanges. 5 The bottom 1 is provided with the end flaps 1^a, and the other portions 2, 3, and 4 are also provided each with flaps 2^a, 3^a, and 4^a, respectively, as in my former application. In forming the tie the flaps are turned in, as described in said application. The base of the tie is filled with concrete 5 in all the forms shown. In Fig. 5 is shown a single filling strip of wood 6 for the upper portion of the tie, as in my former application. In Fig. 6 15 the central portion of the upper part of the tie is filled with concrete, as at 6^a, and the ends are filled with short sections of wood 7, extending from the end about one-third the length of the tie. In Fig. 7 the short strips 20 or blocks of wood 7 are shorter and are arranged in sockets between the middle section 6^a and outer end sections 8 of concrete, said blocks arranged below the rails of the track. In the last-mentioned form drain- 25 passages 9 are formed in the concrete from the sockets to the ends of the tie in order to permit moisture to run off and prevent rotting of the blocks of wood. As shown in Fig. 11, the recess is undercut or stepped at 30 10 at the end nearest the end of the tie, and the block is correspondingly cut, as at 11, to fit thereunder. This formation prevents the rising of the blocks out of the cavities. The blocks are preferably made reversible, as 35 shown, so that they may be removed, inverted, and again inserted for further use. Smaller and shorter blocks of wood than could otherwise be employed in railway construction, including softer woods and even pieces of old 40 ties that are sound, might be used for this purpose, as they are covered by the rail-engaging plates.

The reinforcing angle-bars 12 are permanently riveted to the upper horizontal portions of the casing at 13, as has already been described, and they are secured with the upwardly-extending flanges to the wooden blocks by transverse bolts 14. Said angle-bars 45 greatly strengthen the upper narrow portion 50 of the tie, making it possible to do away with the cover-plate of my former application. The rail-holding plates 13, made, as in said application, either sectional or extending all the way along between the rails, have their outer ends 55 turned over, as at 17, to engage the outer flanges of the rails and are provided with holes along the inner flange for the spikes. I prefer to use a screw-spike 17^a, as shown in Fig. 12, for holding said plate and the rails in place, 60 as its use tends to avoid the shock caused by the hammer-strokes in driving the spikes and also lessens the chances of splitting the wood.

The present invention has all the advantages of my former one and at the same time 65 eliminates the cover-plate and still further re-

stricts the amount of wood consumed in the manufacture of the ties. As in the former case, the parts are made interchangeable.

Having thus described my invention, what I claim as new, and desire to secure by Letters 70 Patent, is—

1. A railroad-tie comprising a casing formed with a broad lower portion or base and a narrower upper portion, a concrete filling for the lower portion and a filling for the upper portion 75 consisting of part concrete and part wood.

2. A railroad-tie comprising a casing formed with a broad lower portion or base and a narrower upper portion, a concrete filling for the lower portion and a filling for the upper portion 80 consisting of part concrete and part wood, and means to retain said wood in place.

3. A railroad-tie comprising a casing formed with a broad angular lower portion or base and a narrower angular upper portion, a concrete 85 filling for the lower portion and a filling for the upper portion consisting partly of concrete and partly of wood.

4. A railroad-tie comprising a casing made from sheet metal and having its sides bent from 90 the base, first upward, then inward and thence upward again forming a broad lower portion and a narrower upper portion, a concrete filling for the lower portion and a filling for the upper portion consisting partly of concrete 95 and partly of wood.

5. A railroad-tie comprising a metallic casing made from a single sheet and having its sides bent from the base first upward, then inward, and thence upward again forming a 100 broad lower portion and a narrower upper portion, a concrete filling for the lower portion and a filling for the upper portion consisting partly of concrete and partly of wood.

6. A railroad-tie comprising a casing made 105 from sheet metal and having its sides bent from the base first upward, then inward, and thence upward again forming a broad lower portion and a narrower upper portion, the extremities of said casing slit and turned inward to 110 close the ends, a concrete filling for the lower portion and a filling for the upper portion consisting partly of concrete and partly of wood.

7. A railroad-tie comprising a casing formed with a broad lower portion or base and a narrower upper portion, a concrete filling for the lower portion extending up into the upper portion at the center and a wood filling for the 115 ends of said upper portion.

8. A railroad-tie comprising a casing formed with a broad lower portion or base and a narrower upper portion, a concrete filling for the lower portion extending up into the upper portion at the center and ends leaving intermediate recesses in said concrete, and blocks 120 of wood arranged in said recesses.

9. A railroad-tie comprising a casing formed with a broad lower portion or base and a narrower upper portion, a concrete filling for the lower portion at the center and ends leaving 125

intermediate recesses below said rails, and blocks of wood arranged in said recesses.

10. A railroad-tie comprising a casing formed with a broad lower portion or base and a narrower upper portion, a concrete filling for the lower portion extending up into the upper portion at the center and ends leaving intermediate recesses in said concrete, and blocks of wood arranged in said recesses, and 10 drain-passages from said recesses.

11. A railroad-tie comprising a casing formed with a broad lower portion or base and a narrower upper portion, a concrete filling for the lower portion extending up into the upper portion at the center and ends leaving intermediate recesses in said concrete, blocks of wood arranged in said recesses, and drain-passages from said recesses to the ends of the ties.

20 12. A railroad-tie comprising a casing formed with a broad lower portion or base and a narrower upper portion, a concrete filling for the lower portion extending up into the upper portion at the center and ends leaving intermediate recesses in said concrete, and blocks of wood arranged in said recesses, each recess having an undercut step at one end, the said wood filling having an extension thereunder.

30 13. A railroad-tie comprising a casing formed with a broad lower portion or base

and a narrower upper portion, a concrete filling for the lower portion extending up into the upper portion at the center and ends leaving intermediate recesses in said concrete, and 35 blocks of wood arranged in said recesses, each recess having an undercut step at the outer end, the said wood filling having an extension thereunder.

14. A railroad-tie comprising a casing 40 formed with a broad lower portion or base and a narrower upper portion, a concrete filling for the lower portion, a filling for the upper portion consisting partly of concrete and partly of wood, and a rail-engaging plate ar- 45 ranged over the wood filling.

15. A railroad-tie comprising a casing formed with a broad lower portion or base and a narrower upper portion, a concrete filling for the lower portion, a filling for the up- 50 per portion consisting partly of concrete and partly of wood, and angular brace-bars arranged in the outer upper angles of said casing, and means to secure the horizontal flanges of said bars to the horizontal portions 55 of said casing.

In testimony whereof I affix my signature in presence of two witnesses.

WILLIAM I. F. HARDEN.
